UNITED STATES PATENT OFFICE

168,344

JUICE MIXER OR SIMILAR ARTICLE

Lee Goldman, New York, N. Y., assignor to Corning Glass Works, Corning, N. Y., a corporation of New York

Application August 28, 1950, Serial No. 11,956

Term of patent 7 years

(Cl. D2—3)

To all whom it may concern:

Be it known that I, Lee Goldman, a citizen of the United States of America, residing at 18 East 93rd Street, New York, New York, have invented a new, original, and ornamental Design for a Juice Mixer or Similar Article, of which the following is a specification, reference being had to the accompanying drawing, forming a part thereof.

Fig. 1 is a perspective view of a juice mixer, showing my new design; and

Fig. 2 is a top plan view thereof.

I claim:

The ornamental design for a juice mixer or similar article, substantially as shown.

LEE GOLDMAN.
